ATTORNEY

UNITED STATES PATENT OFFICE.

CHARLES KUEHNER, OF CRANSTON, RHODE ISLAND, ASSIGNOR TO OTTILIE KUEHNER,
OF PROVIDENCE, RHODE ISLAND.

PIN.

962,360.

Specification of Letters Patent. Patented June 21, 1910.

Application filed November 23, 1908. Serial No. 464,153.

To all whom it may concern:

Be it known that I, CHARLES KUEHNER, a citizen of the United States, residing at Cranston, in the county of Providence and State of Rhode Island, have invented certain new and useful Improvements in Pins, of which the following is a specification, reference being had therein to the accompanying drawing.

10 This invention relates to pins, and has for its object to provide simple, inexpensive and effective means whereby the catch and joint members of the pin may be formed integral with the back plate.

15 In carrying out my invention the pin-tongue retaining member is formed by bending outward a portion of the back plate which renders the joint very strong and durable. The stem of the pin is then passed 20 through an elongated hole in one of the walls of said member, the upper edge of said hole being for the purpose of limiting the upward motion of the pin tongue while the lower edge of the hole forms a fulcrum 25 against which the pin-tongue rests in order to produce sufficient tension to hold the point in the catch member. By this means the pin is firmly supported in the joint and by being limited in its backward motion is 30 more readily passed through the fabric or other material when being applied by the wearer.

Another feature of my invention is that the catch member is elongated on one side 35 so as to extend over and cover the point of the pin-tongue when the same is bent down and retained in the catch.

With these and other objects in view, the invention consists of certain novel features 40 of construction, as will be more fully described and particularly pointed out in the appended claim.

In the accompanying drawings: Figure 1—is a perspective view showing the under- 45 side of the pin with the pin-tongue released from the catch member. Fig. 2—is an enlarged blank illustrating the shape in which the same is cut from the stock. Fig. 3—is a side elevation of the plate showing the pin-tongue retaining member bent inward in a U-shape loop. Fig. 4—is a side elevation 50 of said plate showing the pin-tongue retained in position in its retaining member. Fig. 5—is a sectional view of the plate showing 55 the point of the pin tongue bent around

to engage the catch member, said catch member being of a length sufficient to inclose and cover the point of the pin-tongue. Fig. 6—is a greatly enlarged detail illustrating the method of forming the pin-tongue retaining member integral with the back plate. Fig. 7—is an enlarged view of the pin-tongue having a T-shaped head.

Referring to the drawings 1 designates the front portion of the pin and 2 the back plate thereof over which latter the edge of the former plate may be rolled to secure the two together. This back plate is preferably blanked out of sheet stock and formed a little longer than the body of the front shell into which it is to fit, the catch member 3 is formed integral with said plate near one end thereof. This catch member is formed with a forwardly projecting lip 4 for the purpose of extending over the point of the pin stem to entirely cover and protect said point when held within said catch. The stock forming the back plate is cut out adjacent the other end to form a narrowed portion 2' which is provided with an elongated hole 5 for the purpose of receiving the stem of the pin-tongue. The narrowed portion 2' is then bent or forced outward from the plane of the plate into substantially a U-shaped loop, as illustrated at 6, see Fig. 3, the pin stem hole 5 being in one of the walls of the loop and in position to receive the pin stem therethrough. The end of the back plate adjacent said loop is extended for a slight distance beyond the loop and is disposed to lie in the same plane as the major portion of the back plate, whereby the extended end of the back plate serves to hold the walls of the loop together under that stress which would otherwise tend to separate them. Since the front plate 1, has its edges rolled over the back plate 2 and the said extended end of the same, it firmly supports the loop; and the fulcrum wall of the loop, which is that wall in which hole 5, is formed, is thus held in its related position to the opposite wall forming the loop, against any spreading tendency, which latter exists when the pin tongue is moved to engage the fulcrum wall in entering the catch member.

The pin-tongue 7 used in the joint member is preferably of the type having a T-shaped head 8 and when placed in position with the stem extending through the hole 5

said head will lie in the bottom of the U-shaped member. The walls of the stock 9 above this head are then drawn or forced together thereby forming a strong joint 35 member integral with the back plate, the forming of which member from the stock of the plate naturally shortens up said plate to the required distance to exactly fit into the front cup member as shown in Fig. 1. 40

10 In assembling the front and back plates 1 and 2, it will be noted that by reason of the narrowed portion 2' the edge of the front plate may be rolled over the edge of the back plate in a continuous unbroken flange, 45 which could not be done if the metal forming loop 6 was as wide as the remaining portion of plate 2.

An essential feature of my improved pin is that owing to the slotted hole through 20 the wall of the joint member the backward swing of the pin-tongue is limited, that is, the tongue is allowed to swing back against the outer edge of the slot to that angle from the body which is found in 25 practice to be most advantageous in applying the pin to the goods by the wearer. The pin stem is then carried toward the body portion and brings up against the inner edge of the slot which thus forms a fulcrum sufficient to cause the spring of the pin to 30 firmly hold the point in the catch member.

The device is very simple and inexpensive, also strong and durable in construction and by its use the attaching of the pin is greatly 35 facilitated.

Having thus described my invention, what I claim as new and desire to secure by Letters Patent, is:

A pin comprising a back plate provided 40 with a portion adjacent one end bent to form a loop, the said end of said plate being extended for a distance beyond said loop and being disposed to lie in the same plane as the major portion of said back 45 plate, said loop having one of its walls formed with an opening, a pin tongue having a T-shaped head, the head being pivoted in the loop and the tongue proper extending through said wall opening of the 50 loop and being fulcrumed on said wall of the loop having said opening, and a front plate rolled over the edges of the back plate, whereby said extended end of the back plate is held to firmly support the loop and prevent same from spreading when the pin tongue is moved to engage the fulcrum wall 55 of the loop in entering the catch member.

In testimony whereof I affix my signature in presence of two witnesses.

CHARLES KUEHNER.
